SPRING WINDING MACHINE

Peter J. Bianco, Detroit, Mich., assignor to General Motors Corporation, Detroit, Mich., a corporation of Delaware

Application November 2, 1949, Serial No. 125,077

14 Claims. (Cl. 29—228)

1

This invention relates to spiral or clock type springs and more particularly to a machine for automatically winding such springs and installing them in wound condition in the mechanisms in which they are to function.

Suck clock type springs have come into fairly general use in manually operated window lift mechanisms, deck lid supports, door hinges, etc., of automotive vehicles for example wherein the clock spring exerts a biasing force to fold or unfold a pair of hinged links. Since these springs are most commonly installed in a pre-stressed or partially wound condition, a definite need has arisen for power actuated means to effect this initial spring winding operation and the installation of the pre-wound springs in the mechanisms in which they are to function. This is particularly the case with springs which are relatively stiff and difficult or impossible to pre-wind manually.

Accordingly, it is the principal object of my invention to provide a power operated machine for automatically winding clock type springs and installing them in the mechanisms in which they are to function.

In the drawings:

Figure 1 is a front elevational view of a preferred embodiment of a machine in accordance with my invention for winding and installing springs in automotive vehicle window regulating devices, certain parts being shown in section.

Figure 2 is an enlarged detail view similar to Figure 1 showing the relation of the parts just prior to the start of a spring winding operation.

Figure 3 is an exploded view in perspective of certain parts associated with the lower end of the spring winding ram.

Figure 4 is a perspective view of the cam member for effecting windup of the spring during the driving stroke of the ram.

Figure 5 is an enlarged detail view similar to Figure 1 showing the transfer of the wound clock spring from the cam to the window regulating device.

Figure 6 is a detail sectional view taken on line 6—6 of Figure 1 showing the relationship of the clock spring with the cam during the spring winding operation.

Figure 7 is a fragmentary plan view of a conventional window regulator device with its wound clock spring installed.

Figure 8 is a sectional plan view taken substantially on line 8—8 of Figure 1.

Figure 9 is an enlarged detail sectional view taken substantially on line 9—9 of Figure 1.

2

Figure 10 is an enlarged sectional plan view taken substantially on line 10—10 of Figure 1.

Before beginning a detailed description of the elements shown in the drawings, my machine may be briefly described as comprising a stationary frame supporting a horizontally reciprocating carriage which includes a cam in the form of a hollow tube through which the clock spring to be wound is delivered to the window regulator assembly held in a fixture below. In the initial position of the carriage said tube shaped cam receives one spring from a gravity fed magazine above. Upon starting the machine, the carriage moves horizontally to a position at which the tube is aligned with the spring center post of the window regulator mechanism, following which a vertical ram automatically moves downward and pushes the spring through the tube. In so doing the spring is wound up by the ram holding its inner end against rotation while the outer end of the spring travels in a helical camming slot formed in the wall of the tube. Continued downward movement of the ram pushes the wound spring finally out of the camming tube and onto the window regulator assembly. The ram then automatically retracts and after reaching its upper position the carriage including the camming tube returns to its initial position at which it receives another spring from the magazine. The operator can now replace the regulator assembly with its wound spring with another and the operation repeated.

Referring now to Figure 1 the numerals 1, 2, 3 and 4 designate generally the frame of my machine, the horizontally reciprocable carriage, the vertically reciprocable ram, and the window regulating mechanism, respectively. It will be understood that while I have referred to the carriage 2 and ram 3 as horizontally and vertically reciprocable respectively, it is appreciated that these directions of movement could be interchanged without departing from the principles of my invention.

The machine frame 1 comprises principally a back plate 5 supporting upper and lower shelves 6 and 7. 8 and 9 are gusset plates serving to brace the upper shelf 6 on the back plate 5. Similarly, anchor plates 10, 11, 12 and 13 secure the lower shelf 7 in place. The upper shelf 6 is apertured at 14 for passage of the vertically reciprocable ram 3 and adjacent the latter is provided with an opening through which the lower end of a cylindrical magazine 16 extends. This magazine, which has a slot 17 in its side wall and extending the full length thereof, is

secured to the upper shelf 6 and back wall 5 of the machine frame as by suitable upper and lower brackets 18 and 19. On the lower shelf 7 and directly opposite the ram 3 is provided a platform 26 which is suitably arranged to support and locate the window regulating mechanism 4 while the latter is being delivered its wound clock spring 27.

The carriage 2 includes a plate 30 which as shown in Figure 9 is slidably guided at its front and rear edges between ways 31, 32 and 33 supported in downwardly hanging brackets 34 from the upper shelf 6. This plate 30 is apertured adjacent one of its ends to receive the upper end of the camming tube 36 through which the ram 3 passes in effecting the winding and delivering of a clock spring to the window regulator mechanism 4 below. Directly above the entrance to the upper end of the camming tube 36 is a ring 37 having a slot 37' and bore 38 providing a free sliding fit for the clock spring 27 in its initial unwound condition. The upper end of this bore 38 is chamfered as at 39 (Figure 2) to facilitate the spring dropping into place when the carriage 2 is positioned with the ring 37 directly under the spring magazine 16, at which time the slot 37' in the ring is also aligned with the slot 17 in the magazine. The lower extremity of this bore 38 is provided with an inturned conical shoulder 40 which serves as a shelf for temporarily retaining the spring within the bore 38 during travel of the spring with the carriage from the magazine 16 to its subsequent position under the ram 3. The camming tube 36 which is fixedly secured to the carriage plate 30 directly below and aligned with the ring 37 has a bore 42 of the same diameter at its upper end as that of the restriction provided by the conical shoulder 40. This bore 42 is preferably tapered inwardly from its upper end towards its lower end in order to compensate for the reduction in outside diameter of the springs as they are wound up in being passed through the camming tube 36.

As best shown in Figure 4, this camming tube 36 is provided with a helical slot 43 in its cylindrical wall 44, the helical pitch of this slot being selected to effect the desired degrees of windup of the spring, which in the particular embodiment shown amounts to approximately 130°. The purpose of the slot 43 is to cam the hook shaped outer end 46 of the clock spring 27 rotatively about the axis of the tube 36 during the passage of the spring therethrough. The engagement of the hook shaped outer end 46 of the clock spring with the slot 43 is shown in Figure 6.

The vertically reciprocable ram 3 which serves to push the spring through the camming tube comprises a shaft 50 to the lower end of which is attached a swiveled head 51, the latter being retained thereon by a pin 52 anchored in the head 51 and engaging a peripheral groove 53 formed on the shaft 50. This head 51 as best shown in Figure 3 is generally cylindrical in shape to receive the lower end of the shaft 50 and is provided with a plurality (3 as shown) of slots 54 extending through its side wall and upwardly from its lower end. Hinged fingers 55 swingably carried on pins 56 in the head 51 are positioned in the slots. The upper ends of the fingers 55, above the hinged pins 56, are urged toward each other by a garter type spring 57 which engages the fingers in grooves 58 provided therein and encircles the head 51 within a peripheral groove 59. The lower end of each of

the fingers 55 carries a foot 60 which abuts the upper surface of the clock spring at circumferentially spaced positions thereon for forcing the spring through the camming tube 36. One of the feet 60 is preferably provided with an outwardly extending projection 61 which also engages the helical groove 43 in the camming tube and bears downwardly on the clock spring outer end 46 during winding to insure against any possibility of distortion of the clock spring as might result from the spring's outer end 46 binding in the camming slot 43. A conventional ball thrust bearing 62 (Figure 1) is interposed between the upper end of the head 51 and a shoulder 63 on the shaft 50 to accommodate the relative rotation between the head and shaft resulting from the interaction of the finger projection 61 with the camming slot. It will be understood that the pin 52 has a sufficiently loose fit in the groove 53 to permit the bearing 62 to take the thrust loads on the head during downward movement of the ram. Screws 64 are carried by the upper ends of the fingers 55 in position to abut the periphery of the ram shaft 50 for adjustably limiting the action of the garter spring 57.

Referring to Figure 8 it will be seen that the ram shaft 50 is keyed against rotation about its axis by a key 66 in a slide 67 which is guided for slidable vertical movement in ways 68 and 69 attached to the back wall 5 of the machine frame. An enlargement or collar 70 formed on the upper end of the shaft 50 anchors the latter against longitudinal movement in the slide 67 and is retained in place therein by a cap 71.

Means for effecting the raising and lowering of the ram 3 is provided in the form of a double-acting fluid operated cylinder 74 (Figure 1) in which is mounted a piston (not shown) having a piston rod 75 which is fixedly connected to the slide 67. The laterally extending arm 76 carried by the slide is provided with upwardly and downwardly extending switch actuating cam members 77 and 78.

A similar double-acting fluid operated cylinder 80 (Figure 1) attached to the underside of the upper shelf 6 is provided for effecting the horizontally reciprocating movement of the carriage 2. The piston rod 81 of this cylinder is fixedly connected to one end of the carriage plate 30, and a bolt 82 extending from the opposite end of this plate is arranged to slidably pass through a side portion 83 of the machine frame during carriage reciprocation, the head 84 of this bolt serving as a stop for limiting travel of the carriage to the right as viewed in Figure 1. For limiting travel of the carriage in the opposite direction, there is provided cooperating abutments 85 and 86 which are anchored opposite each other in the carriage plate 30 and the frame portion 83. Other abutments (not shown) may be similarly employed to limit the extreme positions of the vertical ram 3. The carriage plate 30 carries by means of the bracket 87 a switch actuating cam 88.

As means for holding the inner end 89 of the clock spring 27 from rotating during its windup while being pushed through the camming tube 36, the extreme lower end of the ram shaft 50 carries a nose piece 100. This nose piece is in the form of a short rod telescopically slidable in a socket 101 provided in the end of the ram shaft 50. Key 102 carried by the nose piece and slidable in a groove 103 in the wall of the socket 101 serves to prevent rotation of the nose piece in the latter. To provide for retrac-

tion of the nose piece into the socket 101 upon the clock spring 27 being delivered to the window regulator mechanism, a compression spring 104 is located between the nose piece and the inner extremity of the socket 101. A set screw 105 projects through the wall of the ram shaft 50 and into an elongated slot 106 in the surface of the nose piece to retain the latter against dropping out of the socket when the ram is in elevated position. The lower end 107 of the nose piece 100 is bifurcated to receive and hold the inner end 89 of the clock spring against turning during the winding operation. As shown in Figure 5, the bifurcation at the lower end of the nose piece is disposed in the same vertical plane as the bifurcation in the pivot pin 108 which forms a part of the window regulator assembly 4. To ensure against any downward strain upon this pivot pin 108 during installation of the wound clock spring, there is provided an adjustable fixed abutment member 109 having a head 110 at its upper extremity which serves to support the pivot pin 108 as the clock spring reaches its seated position thereon.

Mounted to the back wall 5 of the machine frame are three electric current limit switches 90, 91 and 92 positioned such that depression of their respective spring biased switch operating buttons (93 and 94 for switches 91 and 92 being shown) is subject to engagement by the cams 77, 78 and 88 respectively. By means of conventional electrically responsive valves and interlocking circuit connections (not shown), these switches serve to control the pressurizing of the respective ends of cylinders 74 and 80 to obtain the sequential timing of events in the operation of my machine as will now be described.

In the initial position, i. e., with the machine at rest, the carriage 2 is at its extreme left-hand position with the camming tube 36 directly under the spring magazine 16 from which the lower-most spring 27 will drop by gravity into the ring 37. Ram 3 at this time is at its extreme upper position, its switch actuating cam 77 depressing the switch actuating button of switch 90. Upon the operator manually actuating a starting switch (not shown), fluid under pressure is admitted to the left-hand end of cylinder 80, causing the carriage 2 to travel to the right to its position as viewed in Figure 1. The clock spring to be wound is thus transferred by the ring 37 to a position directly below the ram 3, and the carriage upon reaching this position effects the actuation of switch 92 by the switch actuating cam 88 which in turn causes fluid under pressure to be admitted to the upper end of cylinder 74. As a result, the ram 3 is moved downward, the fingers 55 and nose piece 100 moving into contact with the clock spring in the ring 37 and forcing the spring into and through the camming tube 36. At the start of this downward movement of the ram the switch actuating cam 77 carried therewith moves out of engagement with the contact button (not shown) of switch 90, causing the latter to set up a holding circuit which maintains the pressurizing of the left-hand end of cylinder 80.

The initial downward movement of the clock spring by the ram fingers 55 and nose piece 100 cause the clock spring to contract slightly in passing through the restriction provided by the conical shelf 40 in the bore of the ring 37. As the clock spring continues on downward through the inwardly tapered bore 42 of the camming

tube 36 the clock spring's outer end travels in the helical slot 43 while its inner end is held against rotation by the nose piece 100, and the feet 88 on the ram fingers 55 are caused to bear against the upper surface of the clock spring's outermost convolution due to the lever action produced by the garter spring 57 engaging the upper ends of the fingers 55.

As the ram approaches its lower-most position 10 the clock spring is forced out of the lower end of the camming tube 36 and into its assigned position in the window regulator assembly 4, the upstanding lug 111 of the latter serving to anchor the outer end 46 of the spring as it leaves 15 the camming slot 43 and the bifurcated upper end of the regulator pivot pin 108 simultaneously anchoring the clock spring inner end 89 as it leaves the bifurcation in the nose piece 100 of the ram. As will be clear from Figure 5, the nose piece 100 20 contacts the regulator pivot pin 108 in advance of the ram fingers 55 moving the clock spring to its fully seated position on the regulator assembly, the nose piece biasing spring 104 serving to accommodate the retraction of the nose piece 25 into its socket 101 as the fingers 55 continue moving downward to the limit of travel of the ram.

As the ram reaches its lower-most position, the switch actuating cam 78 carried thereby trips the button 93 of switch 91, reversing the valve setting 30 controlling the pressurizing of cylinder 74 such that fluid is now introduced into the lower end of the latter and the ram 3 thereupon returns to its fully upraised position. Upon the switch actuating cam 77 re-engaging the button of switch 35 90, the pressurizing of cylinder 80 is similarly reversed and the carriage 2 returns to its initial extreme position at which time the lower-most clock spring in the magazine 16 drops into place in the ring 37 preparatory to repeating the cycle just 40 described.

The camming tube 36 now being displaced clear of the window regulator assembly on the platform 26, this assembly can be removed and replaced with another to which a clock spring is 45 to be assembled.

I claim:

1. In a spiral spring winding machine, means for supporting a window regulator device in position for and pending the assembly therewith of a pre-wound clock spring, a cylinder having a helical cam track in its side wall for camming the outer end of the clock spring rotatively about its inner end as the spring is passed coaxially through the cylinder, a ram for effecting the passage of the spring through the cylinder and into assembled relation with the window regulator device, a nose piece projecting from the spring engaging end of said ram and anchored against rotation about the ram axis during said passage of the spring, said nose piece having a portion adapted to engage and prevent rotation of the inner end of the spring during the passage of the spring through the cylinder.

2. In a spiral spring winding machine, a reciprocable ram having means for holding the inner extremity of a clock type spring against rotation about the spring axis while applying an axial force to the outer convolution of the spring, a tube through which the ram is reciprocated provided with a helical cam surface for camming the outer extremity of the spring about its inner extremity during movement of the ram in one direction, and means for effecting the reciprocation of the ram.

3. In a spiral spring winding machine, a non-

rotatable helically slotted member through which a spiral spring may be passed with the outer end of the spring slidably following the helical slot, a ram receivable in said member for effecting the passage of the spring therethrough, means on one end of said ram in abutment with the outer-most convolution of the spring during its passage through the member, and other means on said ram restraining rotation of the inner end of the spring during its passage through the member.

4. In a spiral spring winding machine, a member accommodating the endwise passage therethrough of spiral springs to be wound, a helical cam track within said member for camming the outer ends of the spiral springs about their spiral axis during passage of said springs through the member, a ram arranged to apply endwise thrust to the springs for effecting their passage through the member, and means securing the inner ends of the springs against rotation about the helical axis of the cam track during passage of said springs through the member.

5. In a spiral spring winding machine, a frame, a ram reciprocably mounted thereon including a shaft portion restrained by the frame from rotation about the longitudinal axis of the ram, a head swiveled to one end of said shaft portion, a plurality of spring driving fingers recessed in the outer periphery of said head and hinged thereto intermediate their ends, said fingers extending generally longitudinally of the ram axis and provided with resilient means urging their extended ends outwardly from each other, means limiting the outward movement of said finger ends, a nose piece slidably socketed in the shaft and keyed thereto against rotation about the ram axis, said nose piece having a bifurcated end adapted to rotatively lock the inner end of a spiral spring to be wound, resilient means urging the nose piece outwardly of its socket in the shaft, an inwardly tapered tube into which said ram is reciprocable, said tube being mounted on the frame for reciprocation transversely of the ram, the internal wall surface of said tube being provided with a helical track rotatively camming the outer end portion of the spiral spring being wound during movement of the spring through the tube by the ram, power means for reciprocating the ram, a cylindrical magazine fixed to the frame adjacent the ram for feeding springs to be wound to the tube, and means for reciprocating said tube between positions of alignment with the magazine and ram respectively.

6. In a spiral spring winding machine, a reciprocable carriage including a tube having its longitudinal axis perpendicular to the reciprocatory path of the carriage, said tube having a helical slot in its wall for rotatively camming the outer end portion of a spiral spring about said axis during passage of the spring coaxially therethrough, a stationary spring feeding magazine positioned to register with one end of the tube when the carriage is at one end of its stroke, a reciprocable ram positioned to move coaxially into and out of the tube when the carriage is at the opposite end of its stroke, means on the ram for transmitting end-wise thrust to the outer convolution of the spiral spring, a member on the ram arranged to engage and prevent rotation of the inner end of the spring during movement of the spring through the tube by the ram, means for supporting a spring receiving device in position to receive the spring as the ram ejects it from the tube, and power means for effecting the

reciprocatory strokes of the carriage and ram in timed relation to each other.

7. In a spiral spring winding machine, a frame, a member mounted thereon and provided with a generally cylindrical bore accommodating the endwise passage of spiral springs during winding, the wall defining said bore having a helical slot engageable by the outer ends of the spiral springs during their passage through the bore, said member having a portion provided with an aperture coaxial with said bore through which spiral springs to be wound may be axially advanced into one end of said bore, said aperture including a slot in registry with the adjacent end of said helical slot and an inclined shelf for temporarily retaining a spiral spring prior to its advancement into the bore, a ram mounted on said frame for reciprocation coaxially of said bore, a head swiveled to the ram, fingers pivotally connected intermediate their ends to said head, said fingers having ends adapted to transmit axial thrust to the spiral springs for effecting the advancement of the springs through said aperture and bore, one of said finger ends having a portion arranged to travel in the slots of said aperture and bore during advancement and retraction of the ram, a garter type spring engaging the fingers adjacent their opposite ends and urging their spring driving ends outwardly of each other toward the wall of said bore, and means carried by the ram operative to hold the inner ends of the spiral springs from rotating during their passage through the bore.

8. In a spiral spring winding machine, a frame, a member mounted thereon provided with a generally cylindrical bore for guiding the axial passage of the springs during winding, the wall defining said bore having a helical slot engageable by the outer ends of the spiral springs during their passage through the bore, a ram reciprocably mounted on the frame and rotatively carrying a plurality of fingers arranged to transmit thrust to the outer convolutions of the springs in the bore, one of said fingers having its spring thrust transmitting portion arranged to project into the helical slot, means for urging the thrust transmitting portions of all the fingers outwardly of each other, and a means carried by the ram and slidably keyed to the frame for holding the inner ends of the springs from rotating during their passage through the bore.

9. In a machine for winding spirally preformed springs the opposite ends of which terminate in radially projecting portions, a frame, a ram reciprocably mounted on the frame, a carriage reciprocably mounted on the frame for movement transversely to the ram, said carriage having a spring receivable opening accommodating passage of the ram therethrough when the carriage is at one end of its reciprocatory stroke, a spring magazine fixed to the frame and in spring feeding registry with said opening when the carriage is at the opposite end of its stroke, means within said opening for supporting a spring to be wound while said spring is being transferred from its position opposite the magazine to its position opposite the ram, a camming tube carried by the carriage having a bore aligned with said opening through which the spring may be driven by the ram, the surface of said bore being helically slotted to receive and cam the outer end portion of the spring rotatively about the spiral axis of the spring during passage of the spring therethrough, said ram including a member keyed to the frame against rotation about

said axis, said member terminating in a bifurcation receiving and restraining rotation of the inner end of the spring during its passage through the tube, and means for alternately reciprocating said ram and carriage.

10. In a spiral spring winding machine, a reciprocable carriage including a tube through which the springs are coaxially driven during winding, said tube having an annular bore perpendicular to the reciprocatory path of the carriage, a helical slot formed in the surface of said bore having a continuous rotative camming engagement with the outer ends of the springs during their passage through the tube, a ring mounted on the carriage having means for temporarily supporting an unwound spring in position to enter said tube, a stationary spring magazine in spring feeding relation with said ring when the carriage is at one end of its stroke, a spring driving ram mounted for reciprocation into and out of said ring and tube when the carriage is at the opposite end of its stroke, a frame fixedly supporting the magazine and slidably supporting the carriage and ram, a ram carried member slidably keyed to the frame and adapted to restrain rotation of the inner-ends of the springs as the springs are driven through the tube, and means for reciprocating said carriage and ram.

11. In a spiral spring winding machine, means for guiding axial movement of the spring during winding, a ram for imparting said movement to the spring and having means thereon to restrain rotation of the inner end of the spring about the spring axis during said movement, and a helical cam rigid with said means adapted to impart rotation to the outer end of the spring in response to said movement.

12. In a spiral spring winding machine, a frame, an open ended annular tube mounted on said frame having a bore slidably accommodating the coaxial passage of the springs during winding, a spring driving ram supported on the frame for longitudinal reciprocation into and out of said tube, said ram having a member keyed to the frame and adapted to restrain rotation of the inner end of the spring during passage of the spring through the tube, and a helical cam track on the bore of the tube imparting rotation to the outer end of the spring during passage of the spring through the tube.

13. In a machine for winding spirally pre-formed springs, a frame, a spring driving ram reciprocably mounted on the frame, a tube open at both ends through which a spring to be wound

55

may be axially driven by the ram, said ram having a member on its spring driving end holding the inner end of the spring from rotating during axial advancement of the spring through the tube, said tube having a helical cam surface on its inner periphery adapted to slidably guide the outer end of the spring in a rotary direction during axial advancement of the spring through the tube, and means on the frame supporting said tube during reciprocation of said ram.

14. In a machine for winding spirally pre-formed springs, a frame, an open ended tube mounted on the frame for lateral reciprocation, said tube having a bore accommodating the coaxial passage therethrough of springs to be wound, said bore being provided with a helical slot for receiving and camming the outer end of the spring rotatively about the axis of the tube in response to axial movement of the spring through the tube, a ram mounted on the frame for reciprocation into and out of the tube when the tube is at one end of its reciprocatory stroke, said ram including a shaft portion extending longitudinally thereof and keyed to the frame against axial rotation, a head swiveled to the extended end of said shaft portion, a plurality of circumferentially spaced spring driving fingers recessed in the outer periphery of the head and hinged thereto intermediate their ends, said fingers extending generally longitudinally of the ram and provided with means resiliently urging their spring engaging portions outwardly from each other, a nose piece projecting longitudinally from said extended end of said shaft portion and adapted to lock the inner end of the spring against rotation during movement of the spring through the tube by the ram, means for reciprocating the ram when the tube is at said one end of its stroke, means for reciprocating the tube when the ram is withdrawn from the tube, and means opposite the ram entering end of the tube for temporarily supporting a spring to be wound during movement of the tube toward said end of its stroke.

45
